UNITED STATES PATENT OFFICE.

JOSHUA BAILEY, OF WEST BROMWICH, ENGLAND.

RULING-MACHINE.

1,157,361.

Specification of Letters Patent.

Patented Oct. 19, 1915.

Application filed October 29, 1912. Serial No. 728,383.

To all whom it may concern:

Be it known that I, JOSHUA BAILEY, subject of the King of Great Britain, residing at Bromford Lane, West Bromwich, in the county of Stafford, England, have invented a new and useful Ruling-Machine; and I do hereby declare the following to be a full, clear, and exact description of the same.

My invention comprises improvements relating to ruling machines, and refers to that class of machine which is constructed primarily for ruling, the ruling being effected either by a pen or rotating disk.

The present invention relates more particularly to an improved perforating attachment for such machines.

The object of the invention is to provide an improved attachment wherein male and female perforating members are mounted upon shafts positively connected together by means of gear wheels.

A further object is to arrange the parts so that there is no possibility of the ruling and perforating operations being out of line upon the sheets.

A further object is to divert the ruling blanket from the perforating members, the controlling threads passing between the said members.

The nature of the invention will be further understood from the description of the drawings forming a part hereof and from the claiming clauses.

Referring to the drawings:—Figure 1 is a perspective view showing the application of my invention to a pen ruling machine. Fig. 2 is a diagrammatic section showing the thread control of same. Fig. 3 is a plan of part of a pen ruling machine having my invention applied thereto. Fig. 4 is a longitudinal section through the perforating apparatus and its driving members. Fig. 5 is a perspective view of a part of a disk ruling machine according to this invention; Fig. 6 is a diagrammatic section showing the thread controls. Fig. 7 is an elevation of part of such a disk ruling machine. Fig. 8 is an end view, partly in section, of the perforating rollers of a disk ruling machine embodying the invention.

In applying my invention to a pen ruling machine, as illustrated on the accompanying drawings at Figs. 1 to 4 immediately behind the last row of pens 19 I mount the perforating device which is controlled by three parallel spindles 1, 2, 3, and a roller or drum

4 which are disposed transversely to the travel of the blanket 5, the two outer spindles 2, 3 being at the same height which corresponds with the under side of the blanket when traveling in its normal path. The third spindle does not make contact with either of the other two spindles and is slightly below same, this spindle carrying one of the perforating rollers 9, 10 the periphery of which is at a position corresponding with the top of the blanket.

The three spindles are disposed transversely to the travel of the blanket; being mounted in suitable bearings in the framework 6 at the sides of the machines, and immediately below the middle spindle the aforementioned roller or drum 4 is mounted, this roller being provided at one end with a gear wheel which meshes with a similar gear wheel on the central spindle 1 whereby said spindle and its perforating rollers 9 is rotated.

The blanket passes over the top of the first spindle and then downwardly and around the drum 4 from which it passes upwards and over the third spindle 3, these two spindles and the drum being obviously rotated by the blanket as it travels along. A fifth transverse member 11 is provided above the spindles on which is fitted radial arms 12 each having a set screw 13 whereby they are locked at various angles. These radial arms carry on their extremities another transverse shaft 12^a on which is mounted the second perforating roller 10 which is provided with projecting teeth which engage corresponding teeth on the aforementioned roller carried by the middle spindle, and it will be obvious that as the blanket travels it rotates the drum thus driving the middle spindle with its roller which in turn rotates the second roller 10 and causes the perforating.

The two perforating dies may be rotated by any suitable means. The two perforating disks may be rotated by any suitable means. Preferably we mount the gear wheel 8 on the spindle 11 whereby said spindle and perforator 10 are positively driven.

If desired a pivoted lever 14 may be provided beneath the drum having at its one extremity a roller 15 making contact with the underside of the blanket whereby the blanket is held against the drum, while the other end of the lever is pulled downwardly by means of a spring 16, thereby providing

a positive drive and preventing all liability of the blanket slipping. One or more of these friction grips may be provided if desired.

5. The sheets are passed from the ruling mechanism to the perforating device while still under the same thread control *i. e.* the usual longitudinally disposed threads employed for retaining the sheets in alinement 10 and for conveying the sheets through the machine, these threads being indicated by the lines 18; thereby securing perfect register of the perforations with the ruling on every sheet which passes through the machine. The perforating rollers are laterally adjustable on their spindles, and it will be obvious that more than one pair of rollers may be provided to perforate along more than one line if desired.
20. Although I prefer to fix the perforating attachment in the position above described it may be fixed in any other suitable position, as by continuing the travel of the blanket on to the feed board, to which the perforating apparatus is applied in a similar manner to that described above, the essential condition being that I construct a simple machine for the purpose of performing the two operations of ruling and perforating.

30. The manner of applying my invention to disk ruling machines is illustrated at Figs. 5 to 8, the perforating members 9, 10 being located between the ruling disks 20 and delivery drum in similar manner to that above described in reference to the pen ruling machine, the perforating members being again driven by gears 7 and 8. In this construction of machine there is no blanket the paper being indicated by 17 while two pairs of perforating members are shown.

40. The two operations of ruling and perforating may be performed successively or simultaneously according to the relative position of the ruling and perforating devices.

What I claim then is:—

50. 1. In a perforating attachment for ruling machines the combination of a pair of perforating disks one having a series of male projections and the other having a series of female recesses adapted to perforate the

paper while under the thread control of the machine; transverse shafts carrying said disks; and gear wheels carried by said shafts 55 and positively connecting said shafts and perforating disks together.

2. In a perforating attachment for ruling machines the combination of a blanket; perforating members; controlling threads and 60 means for diverting the course of the blanket from that of the controlling threads at the point where the perforating members are disposed.

3. In a perforating attachment for ruling 65 machines the combination of a thread control; three transverse rollers disposed adjacent to the thread control; a traveling blanket passing around the said rollers and leaving a free space between the blanket and 70 thread control at this point; a transverse shaft located between said blanket and thread control; a perforating disk carried by said shaft; a second transverse shaft located above the thread control and adjacent 75 to the transverse shaft aforesaid; a second perforating disk carried by the second transverse shaft and co-acting with the first disk; a pair of gear wheels on each of said transverse shafts and positively connecting said 80 shafts together and means for adjusting the position of the perforating disks relatively to each other.

4. In perforating attachment for ruling 85 machines the combination of a thread control; a transverse shaft; a male perforating disk carried by said shaft; a second transverse shaft; a female perforating disk carried by said shaft; a pair of gear wheels one on each of said transverse shafts and 90 positively connecting said shafts together; so arranged that the ruling apparatus and perforating disks operate upon the paper while it is under the same thread control to insure perfect alinement of the rulings and 95 perforations.

In testimony whereof, I have signed my name to this specification in the presence of two subscribing witnesses.

JOSHUA BAILEY.
